UNITED STATES PATENT OFFICE

2,211,005

GAS GENERATING APPARATUS

George W. Dick, Lima, Ohio

Application June 27, 1936, Serial No. 87,659

5 Claims. (Cl. 62—1)

This invention relates to gas generating apparatus and more particularly to improved means for progressively converting a highly volatile fuel such as butane from its liquid to its gaseous or vapor state prior to the consumption thereof, although certain features thereof may be employed with equal advantage for other purposes.

It contemplates more especially the provision of simple means for imparting agitation or circulation to the highly volatile fuel such as butane within a confining tank or reservoir so as to utilize the heat of the surrounding medium to progressively effect its transversion from a liquid to a gaseous or vapor state.

15 Numerous types of devices have heretofore been proposed for vaporizing fuel, but these are inefficient, expensive, and embody intricate instrumentalities. Highly volatile fuel such as butane is most efficiently consumed in its gaseous state, and the simplified vaporization thereof renders such more adaptable as a fuel for both domestic and commercial purposes.

Obviously, most fuels can be vaporized by the application of extraneous heat which substantially enhances the cost of such fuel treatment and otherwise complicates the instrumentalities that are necessary for effecting the conversion. With the teachings of the instant invention, it is proposed to utilize the heat inherent in a storage tank that is preferably positioned in the ground below the frost line so that the heat from the surrounding earth may be utilized for conversion of liquid butane to its gaseous or vapor state.

Butane is a by-product of gasoline, and has a boiling point of 33° F. It is the most suitable gas utilizable with the teachings of the instant invention for the purpose set forth, since pentane or commercial gasoline has a boiling point of 94° F. while propane has a boiling point of minus 40° F. Consequently, of these three related fuels, butane is most suitable for conversion into a vapor or gaseous state for efficient consumption to fulfill commercial requirements.

It has been found that the normal ground temperature below the frost line is ordinarily above the boiling point of butane. In consequence thereof, butane is confined in a tank that is buried in the ground below the frost line in any locality in order to impart to the fuel the same temperature as the surrounding earth. The fuel will remain at the same temperature as the surrounding earth so long as the vapor is not withdrawn from the tank. The latent heat of vaporization of butane is approximately 830 B. t. u. per gallon, and as gas or vapor is drawn from the

tank, heat in the above amount must be absorbed from some source in order to permit the transformation from liquid to vapor. This heat comes from the exposed top surface of the fuel, and causes a subsequent drop in the temperature of this surface. In order to secure continuous vaporization, this chilled surface must be replaced with fuel which is warm enough to permit its vaporization, and through the principle of my method and structure, this circulation is repeated continually—the chilled top surface being brought into intimate contact with the shell of the tank, which is of a higher temperature, and the warmer fuel which has not been subjected to the chilling effect of vaporization being brought to the surface.

One object of the present invention is to simplify the construction and improve the operation of devices for converting highly volatile fuels such as butane into a vapor or gaseous state.

Another object is to provide simple, inexpensive and more efficient apparatus for converting liquid butane into a gas for eventual consumption without the aid of extraneous heat.

Still another object is to provide a simple device for association with a storage tank that will progressively convert liquid butane to a gaseous fuel without exercising any care, supervision or utilizing any intricate mechanism.

A further object is to provide a simple and efficient device for converting liquid butane into a gaseous fuel without entailing any labor, instrumentalities requiring maintenance, or other expensive expedients.

A still further object is to provide a simple and inexpensive expedient for progressively converting liquid butane into a gaseous state prior to the consumption thereof.

Still a further object is to provide a storage container with instrumentalities of a simple, inexpensive and fixed type which progressively converts liquid butane into a gas responsive to its consumption without requiring any labor, expensive instrumentalities, or a plurality of liquid fuels to render this accomplishment possible.

An additional object is to provide stationary means in connection with a tank or container for effecting the circulation of its contents so as to absorb the heat from the surrounding medium for conversion of highly volatile fuels such as butane into vapor or gaseous state.

Other objects and advantages will appear from the following description of an illustrative embodiment of the present invention.

In the drawing:

Figure 1 is a sectional view in elevation of a storage tank embodying features of the present invention.

5 Figure 2 is a sectional view taken substantially along line II-II of Figure 1.

Figure 3 is a sectional view in elevation of a modified embodiment of the present invention.

The structure selected for illustration comprises a tank 10 which is of standard design and may vary within a wide range to provide different capacities depending upon the dictates of commercial practice and the requirements of any particular installation. The tank 10 is usually constructed to provide a cylindrical body 11 having circular end enclosures 12 and 13 which are welded or otherwise attached to the cylindrical body 11 to hermetically seal the ends thereof for confinement of liquid, gas or other substances without any possible escape therefrom other than through its discharge orifice provided for that purpose.

In the present embodiment, the body 11 of the tank 10 is provided with threaded flanges 14 and 15 fixed along a top longitudinal median line thereof to enable the attachment of pipes 16 and 17, respectively, which are in threaded engagement therewith. As shown, the pipes 16 and 17 have extensions 18 and 19 confined within the tank 10 so as to define the filling level to which the tank 10 is charged with any liquid. Hand valves 20 and 21 are provided in the intake pipes 16 and 17 which extend upwardly so that the tank 10 may be submerged in the confining earth or ground 22 below the frost line thereof so that the walls will be in direct contact therewith to absorb the heat therefrom.

Obviously, the frost line varies in different localities depending upon climatic conditions so that the depth to which the tank 10 is submerged depends entirely upon local conditions which are easily determined for any particular installation. It is worthy of note that the hand valves 20 and 21 are disposed above the ground 22 so as to be exteriorly accessible for manual control so that the tank 10 may be charged with the liquid fuel such as butane through the pipes 16 and 17 in the customary and well known manner. Further elaboration on the precise method of supplying butane to the tank is thought unnecessary in that this is effected in a manner well known in the art to supply a highly combustible liquid 23 to a maximum level such as defined by the line 24 coincident with the lower extremities of the intake pipe extensions 18 and 19 so as to provide sufficient space 25 above the maximum initial liquid line 24 within the tank 10.

Another pipe 26 is in threaded engagement with a flange 27 welded or otherwise fixed to the body 11 preferably though not essentially in longitudinal alignment with the flanges 14 and 15 described supra. The pipe 26 serves to convey the gaseous fuel from the space 25 to any suitable burner or other apparatus for consumption or use depending upon the purpose of any particular installation. It is proposed to convey only gaseous or vaporous fuel through the pipe 26 from the vapor space 25 situated above the maximum initial liquid fuel line 24. This requires the progressive conversion of the liquid fuel 23 to a vapor or gaseous state responsive to the consumption of the vapor fuel that is conveyed through the pipe 26, it being well known and recognized that vapor or gaseous fuel is far more efficient for consumption than liquid fuel.

To this end the tank 10 is, in this instance, provided with a bulkhead 28 comprising a circular flanged disk that corresponds in diameter with the interior of the tank 10 for welded joiner therewith around the periphery thereof. The bulkhead 28 is welded or otherwise secured to the interior of the tank 10 more proximate to the end 13 thereof to define a comparatively small chamber 29 and a comparatively larger chamber 30, the latter being in communication with the pipe 26 for withdrawing vapor fuel from the space 25 above the liquid fuel level 24. In order to establish comingling of the liquid 23 with the interior surface walls of the tank 10, fuel conduction and transmission between the chambers 29 and 30 is desired. An exchange of fuel from one to the other of the chambers 29 and 30 converts the liquid fuel 23 to a gaseous or vapor state for passage through the pipe 26 that leads to the consumer.

To accomplish this end the chamber 29 is, in this instance, provided with a tubular member such as a pipe 31 that extends downwardly through the top thereof and terminates just short of the bottom 32 of the tank 10. The pipe 31 is attached to a flange 33 provided in the top wall 11 of the tank 10 so as to afford the engagement of an external pipe 34 therewith. The external pipe 34 communicates with the internal pipe and preferably though not essentially extends around the end 13 of the tank 11 to penetrate the earth 22 for a distance substantially below the bottom 32 of the tank 10. The distance to which the pipe 34 extends downwardly into the earth 22 is not of any critical significance, the purpose being to have the pipe 33 absorb the heat of the surrounding earth as the liquid fuel 23 passes therethrough.

As shown, the pipe 34 eventually terminates its downward penetration and thereupon extends horizontally to provide a communicating pipe section 35 which extends for the length greater than the tank 10 so as to provide a communication section 36 upwardly around the end 12 of the tank 10. This increased length of pipe will receive appreciable heat from the surrounding earth 22 and transmit such to the fuel 23 passing through the pipe sections 31, 34, 35 and 36 which has an offset portion 37 engaging a flange 38 fixed to the top of the tank 11 proximate to the end 12 thereof. Another internal pipe section 39 is fixed to the flange 38 to establish communication with the external pipe 37 and provide a vertically depending portion that terminates in an elbow 40 proximate to the bottom 32 of the tank 11 near the end 12 thereof.

Another pipe 41 extends horizontally proximate to the bottom 32 of the tank 10 and is in threaded engagement with the depending pipe elbow 40 so as to communicate therewith and receive the fuel 23 that passes therethrough from the chamber 29 into the chamber 30. The pipe 41 preferably is provided with a plurality of apertures 42 along the length thereof so that the fuel will be discharged therefrom for contact with the interior surface of the tank 10 and absorb more heat from this surrounding medium. In consequence thereof, the vapor fuel confined above the liquid fuel level 24 in the chamber 25 will force the liquid fuel 23 upwardly through the pipe 31 for conduction along the pipe sections 34, 35, 36 and 37 along which path the surrounding earth gives up its heat to elevate the temperature of the fuel that passes through these pipes.

The heated fuel is first transmitted through the external pipe sections 39 and 41 to the chamber 30 so as to trickle through the liquid 23 confined therein and provide effective agitation, circulation and comingling with the other particles of liquid fuel 23 in the chamber 30 so as to substantially increase the rate of conversion from its liquid to its vapor state. A check valve 43 is mounted in the bulkhead 28 near the bottom 32 of the tank and provides for the transfer of liquid fuel 23 from the chamber 30 to the chamber 29 so that the liquid in both of these chambers will be at substantially the same level.

The check valve 43 is of any standard or approved construction and provides for the directional transfer of the liquid 23 from the chamber 30 to the chamber 29, but it does not permit its return therethrough. In order to increase the conduction of the heat from the earth 22 to the interior of the tank 10, it is desirable to provide a plurality of angle irons or flanges 44, in this instance two, that extend longitudinally along the tank 10 in the chamber 30 thereof for attachment thereto so as to increase the radiating surface and thus conduct more heat from the earth 22 to the interior of the tank 10.

Further, a plurality of plates 45, in this instance two, may extend radially from the exterior of the tank 10 (Figure 2) so as to increase the surface area of the tank body 11 and provide increased conduction of the heat to the interior thereof. Any number of these angle irons and plates 44 and 45 may be provided both interiorly and exteriorly of the tank 10 within the dictates of commercial practice, such being optional and depending upon the size of the tank 10 and conditions surrounding any particular installation.

In the modified embodiment shown in Figure 3, the tank 10' has a cylindrical body 11' with the 40 end enclosures 12' and 13'. The bulkhead 28' is provided therein so as to define compartments 29' and 30'. Instead of having the pipes 31—34—35—36—37—39—41 defining a circuitous path around the exterior of the tank 10 as shown and 45 described in connection with the preferred embodiment illustrated and shown in Figures 1 and 2, an elongated pipe 41' may be attached to the bulkhead 28' proximate to the bottom 32' of the tank 10'. The pipe 41' establishes communication between the chambers 29'—30', and it extends laterally for a substantial distance in the chamber 30' and proximate to the bottom 32' thereof.

The pipe 41' is provided with a plurality of 55 apertures 42' along the length thereof so as to provide discharge orifices for the liquid 23' that is exchanged between the chambers 29' and 30'. With this arrangement of parts, the pressure of the gaseous fuel 25' upon the liquid 23' in the 60 chamber 29' will force the liquid 23' along the pipe 41' and discharge such through the apertures 42' so as to rise through the liquid 23' in the chamber 30' and progressively convert such into a gaseous state. This takes place 65 whenever any gaseous fuel is withdrawn through the pipe 26' that leads to the consumer. This constant circulation and recirculation of the liquid 23' between the chambers 29' and 30', effects agitation, circulation and comingling of 70 the warm particles of liquid fuel with the colder particles of liquid fuel to the end of converting such to a gaseous or vapor state and thus fill the unoccupied portion of the tank 10 with the gaseous fuel 25'.

75 The radial flanges 44' may also be provided

in the chamber 30' to increase the heat absorbing surface area of the tank 10' in much the same way as provided and described in connection with the embodiment shown in Figures 1 and 2. Various changes may be made in the embodiment of the invention herein specifically described without departing from or sacrificing any of the advantages of the invention or any features thereof, and nothing herein shall be construed as limitations upon the invention, its 10 concept or structural embodiment as to the whole or any part thereof except as defined in the appended claims.

I claim:

1. In a device of the character described, the 15 combination with a tank for confining a highly volatile combustible fuel, of a bulkhead in said tank for defining adjacent chambers therein, and open by-pass means extending between said chambers to provide for the flow of said fuel 20 along a circuitous path between said chambers for increasing the heat absorption from the wall of said tank for the purpose set forth.

2. In a device of the character described, the 25 combination with a tank for confining a highly volatile fuel, of a bulkhead in said tank defining separate adjacent chambers therein, intake pipes extending through the top of said tank and terminating at a predetermined level in one of said chambers to supply liquid fuel to said level so 30 as to define a gas space therefor, outlet means at the top of said tank for communication with said gas space, and tubular means communicating between said chambers, said tubular means comprising an external pipe encircling said tank 35 and lodged in the earth therebelow to establish communication between said chambers for effecting the flow of fuel therebetween when gaseous fuel is withdrawn through said outlet means, thereby converting liquid fuel to gaseous fuel 40 before the withdrawal thereof through said outlet means.

3. In a device of the character described, the 45 combination with a tank for confining highly volatile liquid fuels, of a partition in said tank proximate to one end thereof to define a large and small chamber adjacent each other, a tube mounted in said partition to establish restricted communication between said chambers to enable the flow of fuel from one chamber to another, 50 said tube extending into the larger chamber proximate to the bottom thereof, said tube having apertures provided therein along the length thereof, means for partially filling said chambers with liquid fuel to provide a gas space there- 55 above in each of said chambers, and means communicating with said gas space in one of said chambers to withdraw gaseous fuel from said tank and progressively convert the liquid fuel to a vapor or gaseous state. 60

4. In a device of the character described, the 65 combination with a tank for confining highly volatile liquid fuels such as butane, of a bulkhead in said tank proximate to one end thereof to define a large and small chamber adjacent each other, there being a restricted port in said bulkhead for enabling said chambers to be partially filled with liquid fuel to substantially the same level so as to provide a gas space there- 70 above in each of said chambers, means communicating with the gas space in said larger chamber to withdraw gaseous fuel therefrom, and a pipe extending externally around said tank with the extremities thereof communicating with each of said chambers to provide for the flow of 75

liquid fuel from one chamber to another so as to effect fuel agitation, circulation and increased heat absorption from said tank for the progressive conversion of liquid fuel to its gaseous or vapor state.

5. In a device of the character described, the combination with a tank for confining highly volatile liquid fuels such as butane, of a bulkhead in said tank proximate to one end thereof to define a large and small chamber adjacent each other, there being a restricted port in said bulkhead for enabling said chambers to be partially filled with liquid fuel to substantially the same level so as to provide a gas means thereabove in each of said chambers, means communicating with the gas space in said larger

chamber to withdraw gaseous fuel therefrom, a pipe extending externally around said tank with the extremities thereof communicating with each of said chambers, and a tube extending along and proximate to the bottom of said larger chamber for communicating with the extremity of said external pipe that extends in said last named chamber to provide for the flow of liquid fuel from said smaller chamber through said bottom tube and into said larger chamber so as to effect fuel agitation, circulation and increased heat absorption from said tank for the progressive conversion of liquid fuel to its gaseous or vapor state.

GEORGE W. DICK. 15
